UNITED STATES PATENT OFFICE

2,631,635

SELF-LOCKING SETSCREW

Paul W. Klooz, West Hartford, Conn., assignor
to The Holo-Krome Screw Corporation, Elm-
wood, Conn., a corporation of Connecticut

Application October 30, 1950, Serial No. 192,975

1 Claim. (Cl. 151—70)

1

The present invention relates to setscrews and more particularly to a novel and improved construction for the nose portion of a setscrew which provides the setscrew with new and unexpected operating characteristics.

The primary function of a setscrew of the type referred to here is to fix the relative position of two members which are otherwise movable relative to each other. The setscrew usually is threadably received in a tapped opening of one of the members and is turned until its nose engages with substantial pressure against the second member. When so employed the pressure on the one hand between the threads of the setscrew and those of the tapped opening in the first member, and on the other hand between the nose of the setscrew and the second member, usually sets up sufficient frictional resistance to prevent any movement of the members relative to the setscrew and to each other. Where the second member is movable in such fashion that the surface thereof engageable by the nose of the setscrew may move laterally by the axis of the setscrew, it frequently is the practice to provide a nose construction in the setscrew in the nature of a point or cup which will imbed itself in the surface of the second member and thus provide additional resistance to the lateral movement referred to.

When a setscrew is turned into place with sufficient pressure to lock the members together, the members and the setscrew are frequently referred to in the art as being "sealed." As long as the members remain in "sealed" relation, i. e., without any relative movement between the members and the setscrew, the effectiveness of the setscrew is at a maximum but any movement of the members or the setscrew causing a break in the "seal" rapidly diminishes the effectiveness of the setscrew. As a general rule, sufficient vibration, etc., will be present to back up the setscrew to disengage the members once the initial "seal" has been broken.

As will be apparent, a frequent cause of the breaking of the "seal" will be a slight turning movement of the setscrew. Accordingly, many attempts have been made heretofore in the art to provide some means for interlocking the nose of the setscrew with the member with which it is engaged. Such means have generally taken the form of cutting or milling devices of various types provided in the nose of the setscrew which operate to cut projections in the engaged member. The object is to cut the surface of the engaged member to form the desired projections without

2

completely severing the same so that some interengagement between the projections and the setscrew is obtained. However, this result is exceedingly difficult to accomplish and the projections usually are severed to some extent, particularly, when the setscrew is backed out of engagement, and this is particularly disadvantageous when the setscrew is used with machinery where the presence of loose metallic particles can cause damage. Furthermore, the effective resistance of projections which are cut in this manner even though not entirely severed is relatively weak and, therefore, does not create any material stabilizing force in addition to that already provided by friction. This is particularly true where the provision of cutting means in the nose of the setscrew diminishes the effective area of frictional contact.

Furthermore, such modified arrangements of the nose of the setscrew have been difficult and expensive to fabricate so that the cost of providing the so-called self-locking feature far exceeds the very limited value and effectiveness of these prior art constructions.

25 It is a principal aim of the present invention to provide a modified nose construction for a setscrew which will cause the engagement of the nose of the setscrew with a metallic member to form a true interlock creating substantial resistance to reverse or disengaging turning of the setscrew.

30 A further aim of the invention is to provide a modified nose construction for a setscrew which will create an interlocking engagement with a metallic member by a molding or swaging action which will not result in undesirable cutting or severing of metallic projections in the member and which will inter-engage with the deformed or swaged portion of the metallic member to substantially resist relative turning movement.

35 A further aim of the invention is to provide such a desired modification of the nose construction of a setscrew which can be easily and inexpensively manufactured with the result that setscrews having the improved characteristics referred to can be made at a negligible, if any, increase in cost and can be easily fabricated without requiring expensive and difficult manufacturing operations.

40 Other objects will be in part obvious, and in part pointed out more in detail hereinafter.

45 The invention accordingly consists in the features of construction, combination of elements and arrangement of parts which will be exemplified in the construction hereafter set forth and

the scope of the application of which will be indicated in the appended claim.

In the drawings:

Figure 1 is a side elevational view of a setscrew embodying the present invention.

Figure 2 is a bottom plan view of the screw shown in Figure 1.

Figure 3 is a vertical cross-sectional view of the screw shown in Figure 1 taken on the line 3—3 of Figure 2.

Figure 4 is a vertical cross-sectional view similar to Figure 3 and showing the setscrew in operative relationship with two relatively movable members.

Figure 5 is a cross-sectional view taken along the line 5—5 of Figure 4 and showing the interlocking deformation of the member engaged by the nose of the setscrew.

Referring to the drawings, a setscrew embodying the present invention is shown, generally, by reference letter A and it includes a generally cylindrical body 10 provided with the usual external threads 12. Any suitable means may be provided to permit turning of the setscrew in accordance with the usual practice. In the exemplary setscrew A shown in the drawing the means for permitting turning of the setscrew is a polygonal socket 13 at the upper end of the setscrew for the insertion of a turning tool. The nose of the setscrew at the end opposite from the polygonal socket 13 is denoted generally by reference numeral 14.

Referring to Figure 4 of the drawings, the setscrew A is shown threadably received in a tapped opening 20 in a first member B with its nose portion 14 engaging a relatively movable second member C. As will be readily understood, the setscrew A is turned inwardly as permitted by its threaded engagement with the tapped opening in member B and its nose portion 14 engages the member C with a combined axial and rotational movement.

In order that the engagement of the nose portion of the setscrew may form an interlocking engagement with the surface of the member C in accordance with the invention, I have found that the nose portion 14 may be formed by providing a pyramidal recess 15 in the nose end of the blank from which the setscrew is formed, such as by punching the same with a punch having a pyramidal head and then chamfering the nose portion to form an outer surface 16 of generally frusto-conical shape.

By so forming the nose portion of the setscrew, it will be observed that there is formed an annular cutting edge consisting of a series of annularly arranged flutes or waves 17. This cutting edge is found to be particularly effective for cutting an annular groove in the member C when the setscrew is turned into engagement therewith with sufficient force or torque.

Immediately above the cutting edge provided by the flutes or waves the nose portion rapidly increases in thickness, being bounded on the outside by a frusto-conical surface 16 and bounded at its interior surface by a plurality of generally triangularly shaped chordally arranged facets 18. Accordingly, as the cutting edge descends into the member C, as a result of the turning movement of the setscrew, the metal of the member C is first cut or severed in an annular line 21 and then the metal on either side of the cut or severance line is forced away from the cut by the descending nose of the setscrew. This causes an annular rim or ridge 22 to be formed in the metal

of the member C extending about the periphery of the nose of the setscrew and at the same time compresses the metal within the pyramidal recess of the nose portion. The final result is that

5 when the setscrew is turned with sufficient torque the metal within the pyramidal recess of the nose portion of the setscrew is compressed to such an extent that it will flow and mate with the interior surface or facets of the setscrew nose. This condition is best shown in Figure 5 of the drawings, it being noted that a frusto-pyramidal projection 23 has been formed interiorly of the annular cut or groove 21 in the surface of the member C which corresponds in shape to the pyramidal recess 15 in the nose of the setscrew whereby the recess 15 operates as a polygonal socket for engaging on the polygonal projection 23, thus greatly resisting any reverse turning of the setscrew.

10 The effectiveness of the interengagement of the frusto-pyramidal projection 23 with the pyramidal recess 15 is substantial and greatly increases the utility and successful operation of the setscrew. As will be apparent, reverse or loosening turning of the setscrew after it has been set 15 in place can be accomplished only by deforming the corners of the projection 23. For example, in a hexagonal socket, the ratio of the largest diameter (across the corners) to the smallest diameter (across the flats) is of the order of 1.1547 20 to 1. There is thus provided a considerable resistance or holding force which is a material addition to the resistance to movement occasioned by friction alone.

25 It will be noted that in the exemplary embodiment shown in the drawings the pyramidal recess has been shown as hexagonal, although it will be realized that a greater or fewer number of sides could be employed. In general, when the number of sides is increased the pyramidal recess 30 more nearly approaches a conical shape, thus decreasing its effective interlocking engagement with the member C. Conversely, when the number of faces or sides is decreased, the amount of 35 swaging or deformation of the metal of member 40 C is increased, with the result that the setscrew becomes increasingly difficult to turn. In general, a six-sided pyramidal recess 15 appears to be a preferred compromise as it provides a desired ease of turning with adequate interlocking.

45 As described above, there has been provided, in accordance with the invention, a novel construction for the nose portion of a setscrew which can be fabricated with a minimum of effort and at 50 extremely low cost and which, at the same time, will provide a true interlocking between the surfaces of the setscrew nose and the workpiece which effectively aids in overcoming the tendency of the setscrew to turn relative to the workpiece when subjected to vibrations, and the like.

55 As many changes could be made in the above construction and many apparently widely different embodiments of this invention could be made without departing from the scope thereof, it is intended that all matter contained in the 60 above description or shown in the accompanying drawings shall be interpreted as illustrative and not in a limiting sense.

65 It is also to be understood that the language used in the following claim is intended to cover all of the generic and specific features of the invention herein described and all statements of the scope of the invention which, as a matter of language, might be said to fall therebetween.

70 I claim as my invention:

A setscrew comprising an externally threaded

body member formed with a frusto-conical end portion having an axially disposed pyramidal recess defined by substantially six inwardly and upwardly converging substantially triangular facets defining the inner surface of an annularly arranged fluted cutting edge, said cutting edge being composed of outwardly convex segments and being adapted to cut an annular groove in a metallic piece and said inner surface being adapted to swage the metal of the metallic piece within the groove into a mating substantially hexagonal pyramidal projection when the nose of the setscrew is turned into the piece, thereby

5
interlocking the nose of the setscrew with the piece.
